DESIGN FOR AN AMUSEMENT MACHINE CABINET

Edward J. Collins, Chicago, Ill., assignor to The Exhibit Supply Company, Chicago, Ill., a corporation of Illinois

Application November 26, 1938, Serial No. 81,393

Term of patent 7 years

To all whom it may concern:

Be it known that I, Edward J. Collins, a citizen of the United States and a resident of Chicago, in the county of Cook and State of Illinois, have invented a new, original, and ornamental Design for an Amusement Machine Cabinet, of which the following is a specification, reference being had to the accompanying drawing, forming a part thereof, and in which:

Fig. 1 is a perspective view of the amusement machine cabinet showing my new design; and

Fig. 2 is a top plan view of the same with the front wall thereof facing to the right.

I claim:

The ornamental design for an amusement machine cabinet, as shown.

EDWARD J. COLLINS.
